UNITED STATES PATENT OFFICE.

THOMAS W. FRANCE, OF PROVIDENCE, RHODE ISLAND, ASSIGNOR TO H. W. BUTTERWORTH & SONS COMPANY, A CORPORATION OF PENNSYLVANIA.

CALENDER FOR TEXTILE AND OTHER MATERIALS.

Application filed September 24, 1924. Serial No. 739,532.

To all whom it may concern:

Be it known that I, THOMAS W. FRANCE, a citizen of the United States, and resident of Providence, county of Providence, and State of Rhode Island, have invented an Improvement in Calenders for Textile and Other Materials, of which the following is a specification.

The improvements comprehending the invention herein set out are adapted for use with calenders generally where provision must be made to permit of variable thicknesses of materials in web form passing between the rolls, but are more particularly intended for use in calenders for pressing or finishing woven cloth in long lengths made up of a plurality of loom length webs sewn or pasted end to end.

Calenders for pressing textile goods in the web provide a nip composed of a top steel roll and a bottom composition roll made of compressed cotton, paper, husk, wool, etc., carefully turned and ground, which latter roll having a somewhat yielding surface is liable under defective operation to be marked by the relatively thick sewed seams of the textile web.

The object of my invention is more particularly to provide calenders employing drop rolls to permit the use of sewed seamed textile fabric in web form with less danger of marking the composite roll and assured calendering close to the seams; and my object is further to furnish capacity to the calender such that the rolls providing the nip may be positively geared together and yet permit compensation through the gearing where, under usage, the composite roll has, before being worn, turned or ground down, been made of a relatively larger diameter than the pitch diameter of the gearing would indicate, so that when gradually reduced in diameter its surface speed when dropped may still reach that dictated by the pitch diameter of the gear, and may even when reduced in diameter below the pitch diameter of the gear have a rotative capacity closely approximating its desirable operation when the nip is in action. Under these objects of my invention, the aim is to provide driving means which, when the roll is dropped, will keep it in motion approximating its normal speed in calendering and instantly "pick up" the nip when it is lifted and at the same time will compensate for speed variations due to

changes in diameter either above or below the pitch diameter of the driving gear, whereby when the roll goes into action with a quick and positive "pick up" no damage will result to the goods or roll in overcoming the inertia of the dead roll, such as occurs when it is only frictionally driven by the other roll in actual calendering, as has heretofore been the customary practice.

My object is also directed to the use of the machine when the steel roll is engraved for producing embossed surface effects upon the goods being calendered and wherein to positively drive the rolls in contact at different surface speeds, however little, would cause the engraved roll to objectionably grind or cut the composite roll.

My object is further to utilize my improvements in cases where the steel roll is smooth, to produce a slight burnishing action upon the fabric to impart luster or sheen to its surface.

By my improvements the calender may be operated with less loss and more assured results in fabric treatment than has heretofore been possible, and this may be obtained with less skill on the part of the operator.

With the above and other objects in view, the nature of which will be more fully understood from the description herein-after, the invention consists in the novel construction of calenders for textile and other materials, as hereinafter more fully described and defined in the claims.

Referring to the drawings: Fig. 1 is a plan view of a calender machine embodying my improvements; Fig. 2 is a horizontal sectional view through the friction drive taken on line 2-2 of Fig. 4; and Figs. 3 and 4 are side elevations of my improved calender.

For more fully disclosing the nature and construction of my invention, I have illustrated the same in connection with a type of calender designed for use in the textile industry and will describe the general construction of the same in connection with my improvements which I have shown as adapted to it, by way of example.

2 is the main frame of the calender, 3 is the upper or steel roll and 4 the lower or composite roll. The lower roll is journaled at each end at 5 in vertically adjustable bearings which are raised and lowered by motive power shown as hydraulic cylinders 7 and 110

plungers or rams 6, to which water under pressure is supplied by pipes 33 and whose supply and exhaust is governed by a valve 33^a and control lever 33^b therefor. By moving the lever 33^b down, the hydraulic pressure on the rams 6 is released and the roll 4 drops; by raising the lever, pressure is applied to the rams and the roll 4 is raised to make the "nip" upon the cloth passing between the rolls. The operator is positioned directly in front of the calender and seeing a seam approaching the nip between the rolls, will quickly push down lever 33^b and thereby instantly drop the lower roll about three-eighths to one-half an inch from the top roll, the seam will pass through and he will quickly throw the lever up again and cause the two rolls to come together again within and pick up rolling contact with the steel roll about four inches from the seam. Ordinarily, the lower roll is driven by frictional contact with the upper roll, which receives motion from an electric motor 16 whose pulley 15 drives a belt 14 and large pulley 13 on a counter-shaft 12 which in turn transmits motion to the roll 3 by a pinion 44 on the shaft meshing with a large gear 19 secured to the roll outside of its bearing. Instead of permitting the lower roll 4 becoming "dead" by losing its rotation when dropped, I provide a geared friction drive whereby the driven roll 3 continually acts to drive the lower roll 4, whether raised or lowered, but especially when lowered so that the lower roll when raised quickly picks up the nip and speed of the steel roll and insures perfect handling of the goods when the seam has passed through the rolls. It further insures prompt calendering action following the passage of the seam and consequently less loss. I will now describe this mechanism embodying my invention.

By reference to Fig. 4, it will be seen that the upper steel roll 3 is provided with a gear 22 on its end and, similarly, the corresponding end of the lower or composite roll 4 is provided with a larger gear 17, but these gears are not in the same plane and do not directly mesh. They are, however, coupled through the medium of three additional gears 18, 20 and 21, the latter frictionally connected to rotate as a compensating unit. From Fig. 1, it will be seen that the gears 22 and 17 revolve in different planes and that the former is geared with compensating gear 21, while the latter is geared with compensating gear 20 through idler gear 18, this latter to insure proper direction of rotation.

The compensating gears are best shown in Fig. 2, from which it will be seen that they embody the following features: A stud 24 is secured at 25 to the side of the main housing or frame 2. Upon the stud 24 there is

journaled a long rotatable sleeve 23 having a flange 24^a at one end to which the gear 21 is secured so that the sleeve becomes in effect the hub of the gear. A loose compensating gear 20 is journaled upon the sleeve 23 so as to revolve thereon when necessary. Between the gears 20 and 21, I arrange a friction disk member 26 of any suitable material. 70 27 is a flanged hub which rotates positively with the sleeve 24 and gear 21 but through a groove 23^a and spline connection 27^a it has freedom of longitudinal movement along the sleeve. Interposed between this flanged hub and gear 20, I arrange another friction disk member 28. A spring 29 surrounds the sleeve 24 and at one end presses upon the flanged hub 27. The other end of the spring rests against the pressure adjusting nut 30 screwed upon the sleeve 24 and having a hand wheel 31 for rotating it to vary the 75 tension of the spring. In this manner, any degree of friction desired may be put upon the disks 26 and 28 so that the gear 20 is more or less positively driven from gear 21. The idler gear 18 is journaled on a stud 19 which maintains it in geared relation with gears 20 and 17. From the foregoing description, it is manifest that when the roll 4 is dropped the train of gears 22, 21, 20, 18 and 17 will keep the lower roll rotating at its normal driven speed, but this may insure an equal or a slightly greater or less surface speed than the surface speed of the steel roll 3, according to the proportions given to the pitch diameters of the gearing. 80 100

If the steel roll 3 is engraved for producing an embossed effect, it is practically essential that it shall pick up the bottom roll 4 while in motion, but the friction applied to gear 20 must be set to the right tension so that the pick up shall take place without any grinding action which would be damaging to roll 4 itself, the steel engraved roll 3, or the cloth. In this case, the friction shall not be excessive, so that while adequate to impart positive rotation to roll 4 when idle for quick pick up action, it will yield to the normal friction between the rolls 3 and 4 to insure identical surface speeds during the calendering and embossing. 105 110 115

If, on the other hand, the steel roll 3 is plain and not engraved, the friction should be adjusted to gear 20, so as to not only pick up the lower composition roll 4 while it is 120 in motion, but at the same time, exert a slight slipping action or friction upon the cloth which gives to it an additional luster, a helpful feature in obtaining the sheen desired on the goods. To secure this burnishing effect, it is manifest that the surface speed of the lower roll must be different than that of the steel roll and this is true whether its surface speed is greater or less than that of the steel roll. 125 130

Aside from any consideration of making the surface speeds of the two rolls different when treating the cloth for sheen effects, the compensating geared friction drive performs its function perfectly in insuring the quick pick up upon passing a seam, for any variation in diameter of the composition roll due to its being turned or ground down for removing markings. This is of great importance of itself, as it saves cloth on the following side of seams while the matter of embossing or producing extra sheen are supplemental and refinements of the use of my invention.

Referring to some of the additional features of the calender shown, the following may be noted: The cloth roll is indicated at 34 as supported upon a mandrel upon which friction to retard rotation may be applied by a brake device 35 of usual construction. The cloth web from the roll then passes over and under adjustable main drag bars 36, thence over and under fixed guide rods 37, thence in contact with the lower nip roll 4, thence between rolls 3 and 4, thence over guide roller 38 to be wound up as finished roll 39 upon a mandrel fitting a socket 40 and rotated thereby. This socket 40 is frictionally driven by a device 41 in frictional contact with a gear 42 which is continuously rotated by a pinion 44 of driven counter-shaft 12 and idler gear 43, all as is well known in machines of this class. The upper or steel roll is hollow and heated internally in any suitable manner as, for example, by steam supplied by pipe 32. In some cases, the heating may be done by small gas jets as is well known to those skilled in the art.

In conclusion, it will be understood that as the roll 3 is being driven continuously at a uniform speed, the special compensating gearing between it and the roll 4 will always be such that when the roll 4 is raised to pick up in producing the nip after passage of a seam, there is no lost motion or backlash. The nip takes place quickly and positively by the rotating roll 4, since the inertia of a dead roll has not to be overcome. The roll 4 is always alive in rotating action and is always sufficiently close in surface speed to that of the steel roll that the pick up is positive and the adjustment of the speed is instantaneous. By the use of gears in close mesh and under definite drag or tension, the compensation required is smoothly performed with a reasonably high speed and efficient production.

It will now be apparent that I have devised a novel and useful construction which embodies the features of advantage enumerated as desirable, and while I have in the present instance shown and described the preferred embodiment thereof which has been found in practice to give satisfactory

and reliable results, it is to be understood that I do not restrict myself to the details, as the same are susceptible of modification in various particulars without departing from the spirit or scope of the invention.

Having now described my invention, what I claim as new and desire to secure by Letters Patent is:

1. In a machine of the class described having a pair of calendering rolls normally rotating in contact, and means for momentarily moving the rolls out of contact for permitting of the passage of a transverse seam in the material being treated, combined with power means for positively rotating one of the rolls continuously at a predetermined surface speed, power means for rotating the other roll at a slightly different surface speed comprising a train of gearing for power transmission from and in accordance with the speed of the first mentioned roll and extending to and including the second mentioned roll and having therein automatic friction compensating means for permitting an automatic smooth change in surface speed of the second mentioned roll after pick up and under control of frictional resistance arising upon the said roll when in contact with the material and first mentioned roll.

2. The invention according to claim 1, wherein further, the compensating train of gearing comprises a plurality of gears in mesh in one plane and driven commensurately with the speed of one roll and a second plurality of gears in mesh in another plane and in driving connection with the other roll, and the compensating means comprises a frictionally arranged yielding couple between the first and second plurality of gears and connecting them across the two planes in driving direction.

3. The invention according to claim 1, wherein further, the compensating train of gearing comprises a plurality of gears in mesh in one plane and driven commensurately with the speed of one roll and a second plurality of gears in mesh in another plane and in driving connection with the other roll, and the compensating means comprises a frictionally arranged yielding couple between the first and second plurality of gears and connecting them across the two planes in driving direction, said frictionally yielding couple consisting of a rotating sleeve rotated by one of the plurality of gears and loosely carrying one of the gears of the other plurality of gears, friction applying means on and rotating with the sleeve in contact with the loose gear on the sleeve for yieldingly driving it, and adjustable means for adjusting the extent of friction applied.

4. The invention according to claim 1, wherein further, the compensating train of

gearing comprises a plurality of gears in mesh in one plane and driven commensurately with the speed of one roll and a second plurality of gears in mesh in another plane and in driving connection with the other roll, and the compensating means comprises a frictionally arranged yielding couple between the first and second plurality of gears and connecting them across the two planes in driving direction, and provided with adjustable means for adjusting the extent of friction of the yielding couple.

5. The invention according to claim 1, wherein further, the compensating means is provided with adjustable means for adjusting the extent of friction therein.

6. In a machine of the character described, the combination of an upper steel roll, a lower composition roll, means to drop and 20 raise the latter under manual control, a gear on the upper roll, a gear on the lower roll,

said gears in different planes, a stud fixed to the machine, a sleeve journaled on the stud and carrying a gear meshing with the gear of the upper roll, a loose gear journaled on the sleeve and geared to drive the gear of the lower roll, means rotating with the sleeve and applying friction to the loose gear thereon to drive it, and spring devices rotating with the sleeve for determining the extent of the friction.

7. The invention according to claim 6, wherein further, the spring devices comprise a coil spring surrounding the sleeve and pressing upon the means for applying friction to the loose gear, and an adjusting nut on the end of the sleeve for manually adjusting the tension of the spring.

In testimony of which invention, I hereunto set my hand.

THOMAS W. FRANCE.
